PHONOGRAPH AND METHOD OF CONTROLLING THE SAME.

Application filed January 8, 1925, Serial No. 1,245. Renewed November 20, 1928.

This invention relates to dictation machines, and in a more specific aspect to dictation machines of the transcribing type.

An object of this invention is to facilitate the operation of the device, to improve its performance and to decrease the assembling cost of the device, the particular improvements herein disclosed being directed to means for controlling the stylus of the dictation machine when the carriage is back-spaced.

In the accompanying drawings, which illustrate one embodiment of this invention,

Figure 1 is a perspective view of the carriage of a transcribing machine, showing one embodiment of the present invention as applied thereto.

Fig. 2 is a side elevation, partly in section, showing the feeding and back-spacing mechanisms for the transcribing machine, and means for controlling the stylus during the backward movement of the carriage, said means being in its normal inactive position.

Fig. 3 is a view similar to Fig. 2, but showing the stylus controlling device in operative position.

Fig. 4 is a bottom plan view of certain parts of the device shown in Figs. 1, 2 and 3, more clearly indicating the preferred shapes of these parts.

Fig. 5 is a perspective view of an auxiliary key adapted to be attached to the usual back-space key to facilitate the operation of the latter.

The phonographic machine shown in the accompanying drawing for the purpose of illustrating this invention, is a transcribing machine and has a carriage 10, mounted on guide rods 11 one of which is shown, and comprising a head 12 adapted to support a sound-box 13 for reproducing the sound recorded on a record 14. The sound-box 13 comprises a diaphragm 15 connected by a link 16 to a lever 17 carrying at its forward end, a ball-shaped stylus 18 which engages the record 14. For the purpose of allowing the stylus 18 to move to and from the record to accommodate itself to records of different thicknesses, the stylus lever 17 is pivoted at 20 upon arms 21 carried by a floating support 22 which has a horizontal pivot 23, in a part hereinafter referred to as fixed in the carriage frame against vertical movement. And, to allow the stylus 18 to freely track the record, that is, laterally follow the grooves of the record, to compensate

for minute differences between the record groove and the feed-screw, the horizontal pin 23 of the lever 22 is mounted in a bracket or support 24 which itself has a vertically disposed pivot 25 mounted on the carriage head 12. The pivot 25 is so located in a plane at right angles to the longitudinal axis of the record to allow the floating support 22 with its stylus lever 17 to swing laterally in following the grooves of the record. The upper end of the pivot 25 has a bearing in a housing 26 in the head 12, and the lower end is held by a bracket 27 secured to the head 12.

In addition to the function above described, the horizontal pivot 23 of the floating-support 22 allows the latter with the stylus-lever and stylus to be raised from record-engaging position when desired. To do this, when it is desired to move the sound-box carriage for any large extent along the record, and when it is desired to remove the record from the machine and place another record upon the machine, the floating support 22 is provided with a depending arm 28 adapted to be engaged by an arm 29 carried by a carriage release lever 30.

This release lever 30 is so arranged that when the operator raises its forward end, its rearward arm 29 engages the arm 28 of the floating support 22, and raises the latter with the stylus from the record surface. At the same time, the arm 29 of the releasing lever engages an arm 31 forming part of a feed-nut 32 which engages a feed-screw 33 of the carriage feeding mechanism, and raises the nut against the tension of a spring 32^a to an operative position, that shown in Fig. 3, out of engagement with the feed-screw 33. When the releasing lever 30 is allowed to return to its lower position under the influence of the spring 32^a, the floating support 22 falls, due to its own weight, and the action of a spring 35 located between the support and an arm 36 on the bracket 24, until the stylus engages the record.

To move the carriage backwardly a small extent, as when it is desired to repeat the dictation just heard, to verify it, the carriage is moved by back-spacing mechanism comprising a back-space lever 37. This lever is mounted upon a tubular bearing 38 cast in the carriage 10, and is provided at its top portion with a lug 39 pivotally carrying a pawl 40^a. When the back-space lever is op-

erated, the pawl 40^a engages a rack 41^a secured to the frame of the machine and forces the carriage backwardly a predetermined amount. To back-space the carriage in excess of this amount, the back-space lever 37 is repeatedly operated.

According to this invention, this back-spacing movement of the carriage 10 is effected without causing the stylus 18 to be raised from and dropped upon the record surface, to thereby avoid producing in the operator's ears, a loud and unpleasant noise. This condition was heretofore tolerated because the stylus, due to its freedom of lateral movement, would not necessarily follow the carriage in its back-spacing movements unless it were raised clear of the record surface.

However, this disadvantage has been overcome by the present invention, by allowing the stylus to remain in engagement with the record and by providing means for holding the stylus against all lateral movement during back-spacing operations, to cause its position laterally relative to the carriage to remain fixed during the back-spacing movement.

Heretofore, it has been proposed to overcome the disadvantageous noise above referred to by allowing the stylus to remain in engagement with the record, drag behind the advancing carriage, and then to bring the stylus to a centralized position with regard to the carriage by a separate and supplemental operation. These suggestions, it was found, had serious objections. Of these, one was that the stylus would be centralized with regard to the carriage at each back-spacing operation, irrespective of its position before the back-spacing operation took place. In some cases, it was found that the stylus would have lagged so far behind the centralized position, before the back-spacing operation was effected, that after back-spacing the carriage and then centralizing the stylus, the stylus would actually have advanced several grooves, if indeed, it had had its ultimate position changed in either direction relative to the record surface. Another one of the disadvantages of the proposed construction was that two operations were required—one to back space the carriage, and another, to centralize or readjust the stylus.

The disadvantages of the proposed constructions are, however, entirely overcome by the present invention, in which, by a single operation, the stylus is locked in any position which it happens to be assuming and the carriage with the locked stylus is back-spaced.

In the accompanying drawings, one particular embodiment of this invention is illustrated, and this embodiment has been found in practice to be satisfactory and probably would be preferred to others under contemplation.

In this form of the invention, the back-spacing mechanism above described is of usual form, such as disclosed in the patent to MacDonald, 1,030,740 of June 25, 1912, excepting, however, that the depression of the back-space key does not raise the stylus from the record-surface. 70

The means disclosed herein for holding the stylus against movement during the back-spacing operation, comprises a clamping-arm 75 40 pivoted at 41 to the sound-box 13 and having an arcuate locking-surface 42 normally adapted to be disengaged from a co-operating locking surface 43 formed on an arm 44 constituting an integral part of the 80 bracket 24 for the horizontal pivot 23 of the floating support 22. The clamping arm 40 is adapted, when operated, to move from the position shown in Fig. 2 to the position shown in Fig. 3 and in the latter position, 85 produces sufficient friction between the co-operating clamping surfaces to prevent the movement of the floating-support 22.

The means for operating the clamping arm 40 comprises an arm 45 pivotally mounted 90 on the carriage frame 10 and having an operating part 46 adapted to engage a depending lug 47 on the clamping arm 40. The arm 45 is rocked when the back-space key is depressed by means of a spring 48 connected to the operating end 46 and also connected at the other end to an ear 49 on an arm 50. The arm 50 is provided with a finger 51^a normally located in a notch 52 in a sleeve 53 secured to the back-space key 100 37. The arm 50 is provided with a square hole adapted to receive the square-end of a shaft 54 to which the feed nut 32 is secured.

When the back-space key 37 is depressed, its sleeve 53 rocks, carrying with it the arm 105 50, so as to rock the shaft 54 and raise the feed nut 32 from engagement with the feed screw 33 to allow the back-spacing operation to be effected. At the same time, the arm 50, by reason of its movement, tensions the 110 spring 48 and causes the arm 45 to rock rearwardly moving the clamping arm 40 into engagement with its co-operating surface on the bracket 24 to lock the stylus against movement. The parts are so constructed 115 that the stylus is locked against lateral movement before the back-space pawl 40^a engages the rack 41^a to back-space the carriage. When the back-space key 37 is released, a spring, not shown, causes it to return to its 120 normal position. In doing so, the sleeve 53 allows the arm 50 to rock clock-wise under the influence of the feed-nut spring 32^a to its normal position. In returning to normal position, the arm 50 by means of an ear 51 125 engaging a projection on the arm 45 causes the arm 45 to also be returned to its normal inoperative position, that shown in Fig. 2.

Thus, it will be seen that the stylus is first clamped and then laterally moved 130

ily with the carriage during the back-spacing operation, and that after the back-spacing operation has been completed, the stylus will be in the same relative position with 5 regard to the carriage as it assumed before the back-spacing operation was commenced.

This invention also provides means for facilitating operation of the back-space key. This means, as shown in the drawings, comprises an auxiliary-key 55 having a large 10 operating surface and having a depending arm 56 which at its lower end is formed integral with a fork 57. The auxiliary-key 55 is mounted on top of the regular key 37 15 with the part 55 resting on the operating part of the key 37 and with the fork 57 straddling the key 37. It is attached to the key 37 in this position by means of a bolt 58 joining the open-ends of the fork 57.

20 Variations and modifications may be made within the scope of this invention and portions of the improvements may be used without others.

Having now described this invention, what 25 is claimed as new, and for which it is desired to obtain Letters Patent, is:

1. In combination, a carriage; a sound box on said carriage; a stylus carrier mounted for lateral movement on the carriage; and 30 means comprising inter-engageable members mounted on the sound box for locking said carrier against lateral movement, relative to the carriage and means for interengaging said locking members in any position of the 35 stylus carrier with respect of the carriage.

2. In combination, a carriage; a sound box secured to the carriage against movement therein; a stylus carrier mounted on the sound box for lateral movement; and means 40 mounted on the sound box for engaging the stylus carrier to hold the stylus carrier against said lateral movement relative to the carriage.

3. In combination, a sound box; a stylus 45 carrier mounted on the sound box for lateral movement; and means mounted on the sound box for engaging the stylus carrier to hold the stylus carrier against said lateral movement relative to the carriage, said means being effective upon said stylus carrier in any 50 position thereof with respect of the carriage.

4. In combination, a sound box; a carriage therefor; a stylus lever support mounted in the sound box for lateral movement; a locking lever mounted on the sound box and having means adapted to engage the stylus lever support and manually operable means on the carriage for moving the locking lever from inactive to active position.

60 5. In combination, a carriage; a sound box on said carriage; a stylus-carrier support mounted on the sound box for pivotal movement; and controllable means mounted on said sound box for holding said support against such pivotal movement.

6. In combination, a carriage; a sound box on said carriage; a stylus-carrier support mounted on the sound box for pivotal movement; a lever mounted on the sound box and capable of engaging the support in any 70 of its positions with respect of the carriage to hold the support in any such position against such pivotal movement; and manually operable means to control the operation of said lever.

7. In combination, a carriage; a stylus-carrier support mounted on the carriage for pivotal movement; a lever mounted on the carriage and capable of engaging the support in any of its positions with respect of 80 the carriage to hold the support in any such position against such pivotal movement; means to engage the lever and cause the same to be operative; and a spiral spring operatively associated with said last mentioned 85 means.

8. In combination, a carriage; a sound box; a stylus-carrier support pivotally mounted in said sound box; a feed-nut mounted on the carriage; a back-space device mounted on the 90 carriage; means operated by the back-space device for moving the feed-nut to inoperative position; and means on the sound box operated as a consequence of such movement of the feed-nut for holding the stylus-carrier 95 support against pivotal movement while the feed-nut is in inoperative position.

9. In combination, a carriage; a sound box; a stylus-carrier support pivotally mounted in said sound box; a feed-nut 100 mounted on the carriage; a back-space device mounted on the carriage; means operated by the back-space device for moving the feed-nut to inoperative position; a lever on the sound box for holding the stylus-carrier support against pivotal movement; an arm on the carriage for engaging said lever to operate it; and a spring tensioned by the movement of the feed-nut to inoperative position 105 for resiliently operating said arm, which in turn operates the lever for holding the stylus-carrier support against pivotal movement.

10. In combination, a carriage; a sound box; a stylus-carrier support pivotally mounted on the sound box; a back-space device mounted on the carriage; a lever mounted on the sound box for holding the stylus-carrier support against pivotal movement; an arm for engaging said lever to operate it; and a spring tensioned by the movement of the 115 back-space device for resiliently operating said arm.

11. In combination, a carriage; a sound box removably mounted in the carriage; a 120 stylus-carrier support pivotally mounted in a sound box; a back-space device mounted on the carriage; a lever pivotally mounted on the sound box to be removable therewith for holding the stylus-carrier support against pivotal movement; and an arm mounted on 125

the carriage and having sliding non-permanent engagement with said lever for operating said lever to cause the latter to hold the stylus-carrier support against pivotal movement.

12. The combination in a phonograph of a carriage, a sound box on said carriage, a stylus carrier on said sound box and movable relative to the sound box, means for moving the carriage, and means carried by the sound box for holding the stylus carrier against movement in one plane during movement of the carriage.

13. The combination in a phonograph of a carriage, a sound box on said carriage, a stylus carrier on said sound box and movable relative to the sound box across the grooves of a record supported adjacent the sound box, a stylus on said stylus carrier, means for

moving the carriage along the record, and 20 means carried by the sound box for holding the stylus carrier against movement relative to the sound box when the carriage is moved to slide the stylus along the record.

14. The combination in a phonograph of a 25 carriage, a sound box on said carriage, a stylus carrier on said sound box and movable relative to the sound box, and means carried by the sound box for holding the stylus carrier against movement relative to the sound 30 box during back spacing movement of the carrier.

the carriage and having sliding non-permanent engagement with said lever for operating said lever to cause the latter to hold the stylus-carrier support against pivotal movement.

12. The combination in a phonograph of a carriage, a sound box on said carriage, a stylus carrier on said sound box and movable relative to the sound box, means for moving the carriage, and means carried by the sound box for holding the stylus carrier against movement in one plane during movement of the carriage.

13. The combination in a phonograph of a carriage, a sound box on said carriage, a stylus carrier on said sound box and movable relative to the sound box across the grooves of a record supported adjacent the sound box, a stylus on said stylus carrier, means for

moving the carriage along the record, and 20 means carried by the sound box for holding the stylus carrier against movement relative to the sound box when the carriage is moved to slide the stylus along the record.

14. The combination in a phonograph of a 25 carriage, a sound box on said carriage, a stylus carrier on said sound box and movable relative to the sound box, and means carried by the sound box for holding the stylus carrier against movement relative to the sound 30 box during back spacing movement of the carrier.
